[57] CLAIM

The ornamental design for a CRT monitor housing, substantially as shown and described.

DESCRIPTION

FIG. 1 is a front, perspective view of the CRT monitor housing showing our new design;

FIG. 2 is a top plan view thereof;

FIG. 3 is a front elevational view thereof;

FIG. 4 is a left side view thereof, the right side view being identical to the left side view;

FIG. 5 is a bottom plan thereof;

FIG. 6 is a rear elevational view of the CRT monitor housing.
